UNITED STATES PATENT OFFICE.

ERNST LUDWIG GEORG CARL THEODOR BIELEFELDT AND RICHARD FRIEDRICH ERNST LEOPOLD SILWAR, OF HAMBURG, GERMANY.

KEYBOARD-PLAYER.

SPECIFICATION forming part of Letters Patent No. 685,245, dated October 29, 1901.

Application filed May 20, 1901. Serial No. 60,969. (No model.)

To all whom it may concern:

Be it known that we, ERNST LUDWIG GEORG CARL THEODOR BIELEFELDT and RICHARD FRIEDRICH ERNST LEOPOLD SILWAR, subjects of the German Emperor, and residents of Hamburg, Germany, have invented certain new and useful Improvements in Keyboard-Players, of which the following is a specification.

The present invention relates to automatic mechanism for attachment to keyboard instruments—for instance, to writing-machines or type-writers arranged and constructed to be operated by means of key-levers for the mechanical execution or reproduction of a greater number of copies of a writing, prospectus, pamphlet, or the like in order to obviate the more tedious and unreliable finger-work.

The present invention has for its object to produce such a mechanism which may be readily attached to any key-lever-operated type-writer, which shall occupy a comparatively small space, shall be exceedingly simple in construction, of low cost, not liable to get out of order, and thoroughly efficient and reliable in operation.

The invention consists in various features of construction, as hereinafter described and claimed.

In the accompanying drawings, Figure 1 is a sectional elevation of the improved attachment mechanism or keyboard-player. Fig. 2 is a plan view of Fig. 1, and Fig. 3 is a view similar to Fig. 1 and showing a modified form of the means for governing the levers or strikers operating the keys or key-levers of the keyboard instrument.

Similar numerals refer to similar parts throughout the several views.

Suitable brackets 1 of a frame or base 2 support a shaft 3, upon which is mounted a drum or cylinder 4, furnished with pins 5 or the like. Rotation is imparted to the drum 4 by means of a grooved pulley 6 (or any other suitable means) and a suitable gearing, which consists of a pinion 7, keyed on the pulley-shaft 8 and engaging a spur-wheel 9 on an intermediate shaft 10. The shafts 8 and 10 are journaled in the brackets 1 and 1* of the frame 2. The rotation of the shaft 10 is transmitted to the drum 4 by means of a pinion 11,

mounted on the shaft 10 and engaging a suitable spur-gear 12, provided on or attached to the said drum 4.

Above the drum 4 the brackets 1 are connected by a suitable traverse or connecting rod 13, upon which are fulcrumed hammer-like levers or strikers 14, corresponding in number with the keys 15 of the keyboard instrument to be operated and being held the proper distance apart by spacing-rings 16. The levers or strikers 14, being guided in slots 17 of a suitable bracket 18, mounted on the base 2, are connected by rods 19 (or any other suitable means) with double-armed levers 20, pivoted between spacing-rings 21 on a connecting-rod 22 of the bracket-wings 18*. The arrangement of the levers 20 is such that their inner ends or noses 23 are in the path of the corresponding pins 5 of the drum 4.

The above-described keyboard-player is intended to be placed and secured in such position to the keyboard-instrument type-writer that its strikers 14 rest upon the corresponding keys 15 of the latter and are normally held in their upper position by the said spring-actuated keys 15. (See Fig. 1.) When a pin 5 of the rotating drum 4, of which pins, for sake of clearness, only a few are indicated in Figs. 1 and 2, strikes against the nose 23 of a lever 20, the latter is rocked thereby, causing the corresponding lever 14 to swing down and push the corresponding key 15, upon which the said striker rests, likewise downward in order to make the required impression. As soon as the pin 5 has passed the nose 23 the released lever mechanism 20 19 14 is returned or raised into its normal upper position by the also released key 15 rebounding or raising under the influence of its spring. (Not shown in the drawings.)

In the modification shown in Fig. 3 the key-striker mechanism 20 19 14 is operated by fingers or pawls 24, pivoted in open cells 25, provided on the periphery of a revolving drum 26. The pawls or fingers 24 are controlled in their position and governed in their action by a perforated sheet 27, similar to a perforated music-sheet, passing around the said cellular drum 25 26, the sheet 27 being supported by a suitable guide-roll 28. When the mechanism is set in motion, the perforated

rated sheet 27 will be drawn over and around the cellular drum. The full parts of the sheet will then close the cells and retain the corresponding pawls or fingers therein, as this is 5 evident from Fig. 3. As soon as a perforation 27* in the sheet 27 registers with a cell 25 the finger 24 of this cell will swing out under the influence of its gravity or weight and enter the said perforation, as this is also ob- 10 vious from Fig. 3. The thus-radiated finger 24 is then carried around by the cellular drum and sheet 27 and brought into contact with the nose 23 in order to trip the lever 20 and to actuate thereby the striker 14 in the man- 15 ner above described with reference to Figs. 1 and 2. The finger 24 having passed the nose 23 and its upper dead-center turns again down into the interior of its cell in order to be retained therein by a full part of the sheet 27 20 or to be allowed to turn outward into a perforation of the said sheet, as the case may be. The pins 5 on drum 4 or the perforations in sheet 27 and the gravity-pawls 24 on drum 25 are, as will readily be understood, so arranged 25 relatively to the levers 20 and the striker-levers 14 that said levers 20 will be actuated in proper succession from the first to the last letter to be mechanically reproduced thereby, as is the case in appliances for mechanically 30 operating musical keyboard instruments or musical instruments of the music-box type—that is to say, instruments in which suitably-arranged pins on a drum or roller are caused to act directly upon sound-producing devices. 35 We are aware that it is not new to mechanically operate the keys of a keyboard musical instrument by means of a drum organized to actuate strikers, which latter operate keys in their proper sequence, according to the se- 40 quence of the notes of a piece of music. We

are also aware that the operation of the keys of a keyboard musical instrument has been controlled by means of a suitably-perforated sheet controlling the movements of dogs or pawls on a revolving drum, which dogs or 45 pawls actuate the operating devices. We are furthermore aware that it is not new to operate the keys of a type-writer for producing printed matter from a perforated tape or ribbon, and we do not desire to claim, broadly, 50 mechanical appliances for actuating the keys of a keyboard instrument for the reproduction of written or printed matter; but

We claim as our invention—

The combination with the keyboard of a 55 type-writer, of an attachment comprising a number of striker-levers 14 equal to the number of keys on said keyboard, said levers having a common fulcrum and being provided at their free ends with a downward projection 60 adapted to bear on the finger-piece of their respective keys, a rock-lever 21 connected to each striker-lever by a rod or wire 19, said rock-levers 21 having a common fulcrum below the striker-levers, a drum revoluble in 65 front of said rock-levers 21 and means connected with said drum and organized to act on the short arms of the rock-levers 21 at the proper time and in proper sequence to actuate the striker-levers and therethrough the 70 keys, substantially as and for the purpose set forth.

ERNST LUDWIG GEORG CARL
THEODOR BIELEFELDT.
